2 Sheets-Sheet 2

UNITED STATES PATENT OFFICE

SATTERLEE T. ARNOLD, OF IRVINGTON, NEW JERSEY, ASSIGNOR TO THE W. S. MILLS COMPANY, OF BRIDGEPORT, CONNECTICUT

RAVELER FOR LOOPING MACHINES

Application filed August 23, 1927. Serial No. 214,793.

This invention relates to a device for unraveling knitted fabric, especially adapted for use in connection with looping machines which unite superimposed edges of knitted goods, as, for example, openings across the foot or toe of knitted hosiery.

When knitted articles, such as stockings, are placed upon the impaling pins of looping machines, or otherwise situated in said machines with edges superimposed to be joined, it is almost always necessary, provided a neat and comfortable jointure between said edges is to be produced, to unravel a part of each article down to the impaled loops.

It is an object of the present invention to provide a device for unraveling knitted fabric, when impaled in a looping or like machine, down to the impaled loops of said fabric, the device having novel and improved features and characteristics of construction designed to accomplish the unraveling operation in more satisfactory and dependable manner than it has been heretofore accomplished.

A further object is to provide a device for unraveling knitted fabric as just stated, which will also include means for cutting the thread of the waste, when unraveled, at suitable location adjacent the impaled loops, and means for carrying said unraveled and cut thread away from the looping machine and depositing said thread clear of said device.

A further object is to provide in connection with the device, a plurality of spaced apart thread cutting members one of which is positively operating in its action and will not fail to cut the thread before allowing passage of an article to the looper, and one of which is situated in advance of said positively acting member and is adapted to cut the thread of an article only when the fabric of said article has been unraveled down to the impaled loops upon reaching said advanced cutting member.

A still further object is to provide in the device, means for cutting the thread of the waste, when unraveled down to the impaled loops, and means for carrying the unraveled and cut thread away from the looping ma-

chine and depositing the thread clear of the device, as already stated, both of which means are of novel, improved and very satisfactory construction.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the appended claims.

In the accompanying drawing forming a part of this specification,

Fig. 1 is a plan view of a part of a looping machine, and a device having the features of the invention applied to said looping machine;

Fig. 2 is an enlarged plan view, partially sectioned, of the device detached from the machine, the thread cutting knives being not shown;

Fig. 3 is an elevational view of the device as seen from the top side of the sheet in Fig. 2;

Fig. 4 is a sectional view taken as on line 4-4 in Fig. 2;

Fig. 5 is a detail side elevational view of the idler roll support;

Fig. 6 is a detail view of the mounting for the movable roll;

Fig. 7 is a detail view of the thread separator and guide;

Fig. 8 is a detail view of a thread cutting knife about to sever the thread of the unraveled waste; and

Fig. 9 is a detail view of the advanced cutting knife about to be pushed aside by advancing fabric which has not been unraveled down to the impaled loops.

With respect to the drawings and the numerals of reference thereon, 10 represents a stationary supporting disc or dial plate of a looping machine of any ordinary or preferred construction, 11 indicates the usual ring of the looping machine, and 12 denotes a pe-

90

85

95

100

ripheral series of outwardly extending impaling pins upon said ring. Loops of fabric to be united are placed over the impaling pins 12 in a well known manner, and the ring of 5 impaling pins is given a revolving movement (the means for revolving said ring being not disclosed) which causes the fabric to be carried to the looper.

The improved raveler of the invention, 10 designated generally at 13, is situated in advance of the looper. It is secured upon the stationary supporting disc or dial plate 10 of the looping machine in any suitable manner, and is adapted to unravel knitted fabric 15 down to the impaled loops of said fabric, to cut the thread of the waste (when unraveled down to the impaled loops) at suitable location adjacent said impaled loops, and to carry the unraveled and cut thread away from the looping machine and clear of the device. 20

Of the improved raveler, 14 denotes a bracket adjustably secured upon the supporting disc or dial plate 10. As shown, a foot 15 of said bracket has a hole 16 receiving a screw 17 entering said dial plate, and said foot also has an arcuate slot 18 receiving a screw 19 entering said dial plate. The screw 17 provides a pivotal support for the bracket, and the arcuate slot 18 provides for a circumferential adjustment of said bracket, as 30 will be obvious.

A driven shaft 20, suitably mounted in the bracket 14, extends radially of the supporting disc or dial plate 10. The inner portion, 35 designated 21, of said shaft 20 is adapted to be operatively connected with a source of power (not shown) capable of rotating said shaft; preferably with the means of the looping machine for revolving the ring 11 and its 40 impaling pins. The outer end of said shaft 20, located as disclosed just beyond the impaling pins 12, fixedly carries a bevel gear 22 which meshes with a similar bevel gear 23 rigid upon a shaft 24 mounted in depending 45 arms 25 of the bracket 14 and situated at right-angles to the shaft 20. See Figs. 1 to 4, inclusive.

A spindle 26 mounted in the bracket 14 and extending upwardly therefrom has fixed to 50 it, as by a set screw 27, a roll 28 the lower portion of which is adjacent to or contiguous with the upper face of said bracket 14. The lower end of said spindle 26 fixedly carries a bevel gear 29 which meshes with a similar 55 bevel gear 30 fixed upon the shaft 24 between the depending arms 25. See Fig. 4.

A spindle 31, mounted in a block 32 pivoted upon the bracket 14 as at 33 and extending upwardly from said bracket, has fixed to it, 60 as by a set screw 34, a movable roll 35 the lower portion of which is also adjacent to or contiguous with the upper face of the bracket 14. The lower end of said spindle 31 fixedly carries a bevel gear 36 which meshes with a 65 similar bevel gear 37 upon said shaft 24, be-

tween said depending arms 25, and opposite the bevel gear 30. See Fig. 4.

A pocket 38 in said bracket 14 houses a coil spring 39 adapted to engage the block 32 with yielding pressure to urge the movable roll 70 35 against the roll 28, and a screw 40 adjustable in an internal thread of said pocket is adapted to engage the end of said coil spring 75 opposite said block 32, whereby said coil spring can be placed under any desired tension to cause said movable roll 35 to engage said roll 28 with any preferred pressure. The arrangement as described provides for slight movement of the roll 35 away from the roll 28 to allow passage of thread of extra 80 thickness, as will be evident. The interengaging teeth of the bevel gears 36 and 37 are of some considerable depth to still remain in engagement even though the roll 35 moves quite a bit away from the roll 28. See Figs. 85 4 and 5.

The bracket 14 is preferably a casting supporting the parts as hereinbefore stated, although said bracket could consist of separate pieces of suitable material properly secured 90 to each other.

An idler roll support 41 pivotally supported upon the bracket 14, as at 42, rotatably carries an idler roll 43 adapted to engage the fixed roll 28. As shown more clearly in Fig. 95 5, the support 41 includes horizontal spaced apart extensions 44 in which a vertical shaft 45 is mounted, said shaft 45 carrying the idler roll. Numeral 46 denotes a soft outer surface of said idler roll, said surface desirably being 100 composed of rubber.

Means is provided for yieldingly urging the idler roll 43 against the roll 28, this means being more clearly shown in Figs. 1 to 4. 47 105 52 is a small bracket secured upon the casting 14 as by a screw 48. 49 is an internally threaded tube of said bracket in which an externally threaded tube 50 is adjustably situated, the outer end of said tube 50 being closed, except for an opening 51 centrally arranged in said 110 outer end. 52 is a plunger extending through the housing formed by the tubes 49 and 50, the inner end of said plunger engaging the idler roll support 41, and the outer end portion of said plunger being slidably located in said 115 opening 51. 53 is a coil spring upon said plunger and within the tube 50, one end of said coil spring engaging the outer end of said tube 50 about the opening 51, and the other end of said coil spring engaging an enlarged part or shoulder 54 of said plunger. Said coil spring 53 thus urges said plunger into engagement with the support 41 to cause said support to position the idler roll into 120 yielding engagement with the roll 28. Evidently, the amount of pressure with which said idler roll 43 engages said roll 28 can be adjusted by turning the tube 50 in the tube 49. See particularly Fig. 2.

Numeral 55 designates threads of waste to 130

be unraveled from knitted fabric; for example, the stockings 56 disclosed in Figs. 1, 8 and 9. To accomplish the unraveling, the end portion of the thread is grasped by the 5 operator and situated, as shown more clearly in Fig. 1, between the roll 28, on the one hand, and the idler roll 43 and the movable roll 35, on the other hand. Through the driving connections for the rolls 28 and 35 as 10 already described, these rolls are rotated, and thus, the thread is drawn from the knitted fabric; that is to say, the stockings are unraveled.

I have disclosed in the machine a plurality 15 of means, or thread cutting members, to sever the thread before allowing passage of an article past the device of the invention to the looper of the looping machine. One of said plurality of means or thread cutters is positive in its action, and one is situated in advance of said positive means and is adapted to cut the thread of an article only when the fabric of said article has been unraveled down to the impaled loops upon reaching said advanced 20 thread cutting means.

Of the positively acting thread cutting means, 57 is a knife preferably fixed in convenient manner upon an arm 58 itself fixed upon the supporting disc or dial plate 10 as at 30 59, said knife 57 being situated as disclosed just in advance of the idler roll 43 and adjacent the inner ends of the impaling pins 12, above said impaling pins. The thread of the waste is situated between the roll 28 and the 35 rolls 35 and 43 when the article is at a distance from the raveler and advancing toward said raveler. When the article has reached the location of the knife 57 the waste has been, in each instance, unraveled down to the impaled loops, and the thread, held taut by the 40 rolls 28, 35 and 43, is brought into contact with said knife 57 which, naturally, severs the thread. See Fig. 8. Provided the thread has been unraveled down to the impaled loops before the article reaches the 45 knife 57, the rolls 28, 35 and 43 ride over said thread, in a manner not sufficiently heavy to break the thread, until the thread is brought to the knife 57, as will be understood.

50 Of the thread cutting means situated in advance of the positive means for cutting the thread and adapted to cut the thread of an article only when the fabric of said article has been unraveled down to the impaled loops upon reaching said advanced thread cutting means, 60 is the knife preferably fixed in convenient manner upon an arm 61 itself pivoted as at 61' upon the supporting disc or dial plate 10, 62 is a coil spring, secured to the arm 55 as at 63 and to the member 10 as at 64, urging said arm forwardly, and 65 is a stop, upon the member 10, limiting movement of the arm toward forward direction when said arm is positioned about radially of the member 10 60 and is situated adjacent the inner ends of the

impaling pins 12, above said impaling pins. As will be plain from Fig. 9, should the fabric 56 upon reaching the location of the knife 60 be not unraveled down to the impaled loops, said fabric will throw the knife 60 to 70 the inner side of the fabric, against the action of the coil spring 62, and the fabric will pass with thread uncut. But should the fabric be completely unraveled at this time, the spring 75 pressed knife 60 will cut the thread in about the manner that the knife in Fig. 8 is shown ready to make a cut, as will be evident. When the knife 60 is pushed aside by the fabric, it will return to its normal position as in Fig. 1 immediately upon being released by 80 said fabric. The purpose of the knife 60 is to sever any threads which may have become unraveled down to the impaled loops at considerable distance from the unraveling rolls, to thus take off of said rolls the work required 85 to be done when threads are slipping over the rolls, and also to take off of the threads the strain which would otherwise be put upon said threads, tending to break them, or perhaps to damage the impaled loops.

90 Numeral 66 represents a thread separator and guide secured as at 67 upon the bracket 14 and extending upwardly and inwardly above the impaling pins. The upper, oblique edge of the guide is serrated as at 68, the serrations providing ways each adapted to receive a thread, whereby the threads may be spread out, one above the other, along the lengths of the rolls. The screw 67 provides means for supporting the separator and guide 95 66 at any desired angle of inclination calculated to produce the best separating and guiding result of the thread, said screw being a pivot for said separator and guide when not turned down, and fastening the separator and guide in oblique position when turned down. See Fig. 7.

Mechanism represented generally at 69 is for the purposes of stripping the threads from the rolls of the raveler, guiding said threads 100 away from the looping machine, and carrying the threads, when severed, clear of the raveler. Of this mechanism, 70 is a member supported upon the bracket 14 and shaped to provide an expanding chute 71 at the side of 105 the rolls opposite the impaling pins and below the elevation of said rolls, and 72 designates strippers upon said member 70 for insuring that the thread upon passing through the rolls will travel to the chute and clear of the device. The chute 71 can be of any construction suitable to its purpose. As disclosed, it extends obliquely downward in direction away from the impaling pins. The strippers 72 are at opposite sides of the inner end of the chute, 110 one of said strippers being adapted to yieldingly engage the peripheral surface of the roll 28, and the other being adapted to yieldingly engage the peripheral surface of the roll 35. Each stripper extends a sufficient distance 115

along the length of the roll it engages to insure that all threads placed between the rolls will be properly stripped and carried to the chute. As disclosed more clearly in Figs. 2 and 3, each stripper 72 has an ear 73 preferably at the midwidth of its lower edge receiving a screw 74 entering the member 70 to pivotally attach the stripper in upstanding position upon said member. A coil spring 75 for 10 each stripper, situated upon a pin or peg 76 upon the member 70, has a leg 77 fixed to said member as by a screw 78 and a leg 79 engaging the outer, rearward face of the stripper to urge the inner edge of said stripper against 15 a roll 28 or 35, as the case may be.

It will be apparent from Figs. 3 and 4 that the movable roll 35 is somewhat shorter than either the roll 28 or the idler roll 43. This is for the purpose of making easier the insertion of the threads between the rolls at the start of the unraveling operation. It will be evident that as the threads are being inserted, first between the roll 28 and the idler roll 43, and then between said roll 28 and the movable 20 roll 35, said idler roll and movable roll will readily move slightly away from the roll 28 against the action of the coil springs 53 and 39, respectively, and said coil springs will cause the threads to be engaged between the 25 rolls during the unraveling operation under a pressure predetermined by the tension under which said springs 53 and 39 have been placed. The soft peripheral surface of the idler roll 43 will cause all of the threads, some of greater 30 cross-sectional area than others, to be fed at uniform speed through and between the rolls. 35

Having thus fully described the invention, what I claim as new and desire to secure by Letters Patent is:

40 1. The combination with a looping machine, of a device for unraveling thread of fabric down to loops of said fabric impaled in said looping machine, said device being adapted to feed said thread while unraveling 45 in direction away from said looping machine and said device, means for severing said unraveled thread from said fabric, and mechanism for causing said unraveled and severed thread to leave said looping machine and said 50 device.

2. The combination with a looping machine, of a device for unraveling thread of fabric down to loops of said fabric impaled in said looping machine, means for severing 55 said thread when unraveled, said unraveling device being adapted to feed said thread, both while unraveling and after severed, in direction away from said looping machine and said device, and mechanism for depositing 60 said unraveled and severed thread clear of said looping machine and said device.

3. The combination as specified in claim 2, and means for guiding said thread to said 65 unraveling device.

4. The combination with a looping ma-

chine, of rolls for unraveling thread of fabric down to loops of said fabric impaled in said looping machine, means for stripping said thread from said rolls, and means for severing said thread when unraveled, said unravelling rolls being adapted to feed said thread, both while unravelling and after severed, to cause said thread to be deposited clear of said rolls.

5. In combination with a looping machine, 75 a device of the character described, comprising rolls adapted to unravel thread of fabric down to loops of said fabric impaled in said looping machine, said device including a roll having an axis fixed relatively to said device and adapted to be driven, a roll having an axis movable relatively to said roll with fixed axis and adapted to engage with yielding pressure against said roll with fixed axis, 80 said movable roll being adapted to be driven, and an idler roll having an axis movable relatively to said roll with fixed axis and adapted to engage with yielding pressure against said roll with fixed axis.

6. In combination with a looping machine, 90 a device of the character described, comprising rolls adapted to unravel thread of fabric down to loops of said fabric impaled in said looping machine, said device including a roll having an axis fixed relatively to 95 said device and adapted to be driven, a roll having an axis movable relatively to said roll with fixed axis and adapted to engage with yielding pressure against said roll with fixed axis, said movable roll being adapted to be driven, and an idler roll having an axis movable relatively to said roll with fixed axis and having a relatively soft peripheral surface adapted to engage with yielding pressure 100 against said roll with fixed axis.

7. In combination with a looping machine, 105 a device of the character described, comprising rolls adapted to unravel thread of fabric down to loops of said fabric impaled in said looping machine, said device including 110 a roll having an axis fixed relatively to said device and adapted to be driven, a roll having an axis movable relatively to said roll with fixed axis and adapted to engage with yielding pressure against said roll with fixed axis, said movable roll being adapted to be driven, an idler roll having an axis movable relatively to said roll with fixed axis and adapted to engage with yielding pressure 115 against said roll with fixed axis, and means 120 for guiding said thread to said rolls.

8. In combination with a looping machine, 125 a device of the character described, comprising rolls adapted to unravel thread of fabric down to loops of said fabric impaled in said looping machine, said device including a roll having an axis fixed relatively to said device and adapted to be driven, a roll having an axis movable relatively to said roll with fixed axis and adapted to engage with 130

yielding pressure against said roll with fixed axis, said movable roll being adapted to be driven, an idler roll having an axis movable relatively to said roll with fixed axis and 5 adapted to engage with yielding pressure against said roll with fixed axis, said thread being adapted to be placed between said roll with fixed axis and the movable and idler rolls, and said rolls being adapted to frictionally engage said thread to feed the same, and a thread cut-off knife interposed between said impaled fabric and said rolls, said rolls being adapted to hold said thread taut while 10 said looping machine carries the thread to 15 said cut-off knife.

9. In combination with a looping machine, a device of the character described, comprising rolls adapted to unravel thread of fabric down to loops of said fabric impaled in said 20 looping machine, said device including a roll having an axis fixed relatively to said device and adapted to be driven, a roll having an axis movable relatively to said roll with fixed axis and adapted to engage with yielding 25 pressure against said roll with fixed axis, said movable roll being adapted to be driven, an idler roll having an axis movable relatively to said roll with fixed axis and adapted to engage with yielding pressure against said 30 roll with fixed axis, and means for severing said thread when unraveled.

10. In combination with a looping machine, a device of the character described, comprising rolls adapted to unravel thread 35 of fabric down to loops of said fabric impaled in said looping machine, said device including a roll having an axis fixed relatively to said device and adapted to be driven, a roll having an axis movable relatively to said 40 roll with fixed axis and adapted to engage with yielding pressure against said roll with fixed axis, said movable roll being adapted to be driven, an idler roll having an axis movable relatively to said roll with fixed axis and 45 adapted to engage with yielding pressure against said roll with fixed axis, means for severing said thread when unraveled, and means for stripping said thread from said rolls.

50 11. The combination as specified in claim 10, and a chute for carrying said unraveled and severed thread away from said device.

12. The combination with a looping machine, of means for unraveling thread of 55 fabric down to loops of said fabric impaled in said looping machine, and a plurality of spaced apart thread cutting members one positive in its action to cut said thread before allowing passage of fabric having said thread to a looper of said looping machine, and one situated in advance of said positively 60 acting member and adapted to cut a thread of a piece of fabric only when the fabric having said thread has been unraveled down to

said impaled loops upon reaching said advanced thread cutting member.

Signed at Bridgeport, in the county of Fairfield, and State of Connecticut, this 17th day of August, A. D. 1927.
